[57] CLAIM

The ornamental design for a golf putter head, as shown and described.

DESCRIPTION

FIG. 1 is an isometric view of the golf putter head of the present invention;

FIG. 2 is a top plan view of the golf putter head of FIG. 1;

FIG. 3 is a side elevation view of the golf putter head of FIG. 1;

FIG. 4 is a second, opposite side elevation view of the golf putter head of FIG. 1;

FIG. 5 is a bottom plan view of the golf putter head of FIG. 1;

FIG. 6 is a front elevation view of the golf putter head of FIG. 1; and,

FIG. 7 is a rear elevation view of the golf putter head of FIG. 1.

The broken line showing of a hosel and fragmented shaft is for illustrative purposes only and forms no part of the claimed design.
